KEY

Sam Reisner, Pacific Palisades, Calif., assignor to
Oesco Corporation, a corporation of California

Filed July 30, 1968, Ser. No. 12,960

Term of patent 14 years

Int. Cl. D8—03

U.S. Cl. D8—136

FIG. 1

FIG. 2

FIG. 3

FIG. 4

FIG. 5

The dotted line showing in FIGURE 1 is for illustrative purposes only.

I claim:

The ornamental design for a key, substantially as shown and described.
